UNITED STATES PATENT OFFICE.

CHARLES E. McMANUS, OF NEW YORK, N. Y.

CORK-ROD-EJECTOR MACHINE.

1,409,224.

Specification of Letters Patent. Patented Mar. 14, 1922.

Application filed May 28, 1921. Serial No. 473,427.

To all whom it may concern:

Be it known that I, CHARLES E. McMANUS, a citizen of the United States, residing at the borough of Manhattan, in the city, county, and State of New York, have invented certain new and useful Improvements in Cork-Rod-Ejector Machines, of which the following is a specification, reference being had therein to the accompanying drawings, 10 which form a part thereof.

My invention relates to cork rod ejector machines, and more particularly to a machine adapted to force composition cork rods from within the tubes in which they are 15 formed, the functioning of the machine being automatic.

Cork rods to be ejected by a machine embodying my invention are used extensively in the production of sealing disks for bottle 20 caps, it being merely necessary to slice such rods into disks of the required thickness preparatory to assembling them in the bottle cap structure. Such rods are formed by packing granular cork having a thin film of a suitable binder thereupon, in metallic tubes, 25 which tubes and their contents, to wit—the closely packed and cemented granules of cork, are passed through a vulcanizing or baking oven. As a result of the application 30 of heat to the cork composition, the mass thereof will expand, but both ends of the tube being closed to check elongation of the rod in the tube, such expansion serves merely to supplement the packing machine in securing 35 the desired density in the mass of composition in the rod.

With this premise, the machine of my invention is designed to force the completed rods from their inclosing metallic tubes with 40 a rapidity which will give to the machine capacity approximating that of the baker with which it is associated, and without injury to the rods.

To secure the desired result, it is necessary 45 to provide a machine embodying therein a plunger, the stroke of which substantially equals the length of the tubes containing the cork rods, and a suitable intermittently actuated feeding mechanism for delivering 50 the tubes consecutively, or in small groups with relation to the plunger mechanism. The rods are fed to the machine in bulk, being accurately positioned with relation to 55 said plunger mechanism, and intermittently advanced in synchronism with the function-

ing of said plunger mechanism so as to cause each reciprocation of the plunger or plungers to eject each rod in a position where it may be received by the operator of the machine, or delivered to some other mechanism, if desired. The end plug is removed therefrom immediately upon the ejection of the rod or prior to the delivery thereof to the slicing machine.

The intermittent actuation of the feed 65 mechanism must therefore not only be timed with relation to said plunger mechanism, but must be sufficiently precise as to its quantity of feeding movement to accurately position the filled tubes and thus avoid collision 70 between the plunger end and the end of the metallic tube.

The receiving chute, or hopper, adapted to receive the packed tubes in bulk, is so constructed as not to require any accuracy of the 75 positioning of the tubes when feeding the machine, the mechanisms of the machine not only properly placing the tubes with relation to each other, but shifting them transversely of the machine, when necessary, so as to 80 bring them between substantially rigid walls having openings therein for the passage of the plungers and for the movement of the rods from the tubes, thus causing said tubes to be rigidly held against displacement transversely of the machines, means being provided adjacent the plunger mechanism for preventing their vertical displacement.

The capacity of the machine may be varied according to the number of plunger rods 90 used, it being possible to use one or more plungers, as desired, although experience has demonstrated that an operator can work to the best advantage when using two plungers. This capability of variation in the number 95 of plungers, requires a selectively operative actuating means for the tube feeding mechanism, or a variation in the speed of said mechanism in direct ratio with the number of plungers used.

Since there is a slight tendency for the rods to adhere to the inner wall of the tubes, I preferably provide a plunger mechanism which will be so actuated as to start the ejecting action at low speed so as to break 100 any slight bond between the rod and the tube, after which, the speed of the tube is immaterial. By using a crank and pitman driving mechanism for the plunger, I secure a slow start in the feeding movement of the 110

rods, and toward the end of said movement, which latter will facilitate the grasping of the ejecting rods by the operator.

The invention consists primarily in a cork rod ejector machine embodying therein a reciprocatory plunger, oppositely disposed means having openings therethrough adapted to guide said plunger, and permit the passage of a cork rod from a tube, respectively, while holding the tube against movement with the plunger, intermittently operative feeding means adapted to accurately position the tube with relation to said oppositely disposed means, and means adapted to receive tubes and position them with relation to said feeding means whereby they will be successively delivered thereto; and in such other novel features of construction and combination of parts as are hereinafter set forth and described, and more particularly pointed out in the claims hereto appended.

Referring to the drawings,

Fig. 1 is a plan view of a machine embodying my invention, a portion thereof being broken away and condensed;

Fig. 2 is a front elevation of the end plate at the delivery end of the machine;

Fig. 3 is a section on the line 3—3 of Fig. 2;

Fig. 4 is a section on the line 4—4 of Fig. 1;

Fig. 5 is a side elevation of a portion of the feed chain;

Fig. 6 is a section on the line 6—6 of Fig. 5;

Fig. 7 is an end view of the machine broken away and condensed;

Fig. 8 is a section on the line 8—8 of Fig. 7, showing the actuating means for the feeding mechanism when two plungers are used; and

Fig. 9 is a section on the line 9—9 of Fig. 7, showing the actuating means for the feeding mechanism when but a single plunger is used.

Like numerals refer to like parts throughout the several views.

In the embodiment of my invention shown in the drawings, I employ at one end of the machine, a hopper or chute having side walls 10 and 11 and an open bottom containing inclined runways 12, the packed tubes being delivered to said chute or hopper in bulk and without regard to their lateral position and being adapted to descend by gravity toward the bottom of the inclined ways 12.

The side walls 10 and 11 merge into parallel guide walls 13 and 14 spaced apart a distance substantially equalling the length of the tubes, either or both of the side walls 10 and 11 being laterally pitched with relation to its co-operating guide wall 13 or 14 to afford sufficient clearance in the chute or hopper to avoid the necessity for any accurate positioning of the tubes therein.

While the tracks or ways 12 have a downward pitch, the guide walls 13—14 have an upward pitch, shown more particularly in Fig. 4, and terminate adjacent oppositely disposed plates or frames 15 and 16, the former of which has a guide opening or openings therethrough for the plunger, or plungers, to be hereinafter referred to, and the latter of which has an opening or openings therein through which the cork rods 75 may be ejected. The openings in the plate 16 should be slightly larger than the inside, and smaller than the outside diameter of the tubes, so that this plate will receive the thrust on the tubes resulting from the tendency of the cork rods to adhere to the inner wall of the tubes as they are being ejected therefrom.

Co-operating with the supply hopper or chute, is an intermittently operative feeding mechanism consisting of sprocket chains 17—18, the alternate links of which have outwardly projected fingers 19 so spaced as to permit a tube to be contained between succeeding fingers, while accurately positioning a group of tubes with relation to each other and to the openings in the plates 15—16 when a plurality of such openings are used. Said chains pass about sprocket wheels carried by the shafts 20, 21 and 22 respectively, the shaft 22 being a driving shaft, and the other two merely idling shafts, an arrangement which is merely a matter of convenience for closely associating the power for actuating the feeding mechanism with the power for actuating the plunger mechanism, and permitting both mechanisms to be driven from the same source of power and in synchronism, so as to properly time the actuation of the feeding mechanism with that of said plungers. The shaft 20 is upon a lower plane than the shafts 21 and 22 so as to cause the upper reach of the chain between the sprockets upon the shafts 20 and 21 to substantially coincide in pitch with the 110 guide walls 13 and 14.

The fingers 19 upon the feed chains 17 and 18 which are rectilinearly arranged with relation to each other, will ensure the tubes contained in the hopper or chute being fed one at a time in properly spaced positions, and will prevent movement of the tubes from the hopper or chute except under the control of the feed chain, and one at a time.

Extending from the plate 15 are guides 23 having mounted thereon, a cross head 24 carrying one or more plungers 25, one end of said plunger or plungers having a free sliding fit in the opening or openings in the plate 15. Said cross head is connected with a gear wheel 26, driven from any desired source of power, by means of the pitman 27, a construction which permits the starting of said tubes at low speed and a slowing down of the speed thereof toward the end of their 130

stroke, thus avoiding any substantial compression of the cork rod within the tube during the initial application of the thrust of the plunger against same, and facilitating 5 the breakage of any bond between the rod and the wall of the tube, although the composition of the binder employed is such as to minimize any such tendency.

The tube feeding mechanism is driven 10 from the shaft of the wheel 26 by means of the chain and sprocket mechanism 28, geared by means of the intermeshing bevelled gears 29 with a cam shaft 30, the number of cams upon said shaft corresponding with the number of openings in the plates 15 and 16 and the height of the rise of the different cams being in direct ratio with the number of openings. These cams are selectively operative according to the set of the machine.

20 I have found in actual practice that the machine can be operated at an effective maximum capacity when using but two plungers, although it is apparent that the number of plungers may be increased, if desired. When but two plungers are used, the shaft 30 will have thereon two cams 31 and 32, the throw of the cam 31 being approximately twice that of the cam 32 so that with each rotation of the cam shaft, 30 when the cam 31 is operative, the chains 17 and 18 will have a movement corresponding to the distance between the centers of the adjacent fingers 19, and when the cam 32 is operative, the movement will be just twice 35 that resulting from the actuation of the cam 31. Adjacent the shaft 30 is a counter shaft 33, geared to the shaft 22 by means of the intermeshing gears 34, said shaft having mounted thereon two ratchet wheels 35-36 40 having associated therewith respectively the swing frames 37 and 38 carrying gravity pawls 39 and 40 respectively co-operating with the ratchet wheels 35 and 36. By this construction the chains 17 and 18 will be 45 intermittently advanced by a rapid movement and will have a dwell of sufficient length to permit the plungers to eject the cork rods from the tubes.

When conveying the tubes from the hopper or chute, slight flexibility in the chain does not impair the efficiency of the machine, but flexure of the chain intermediate the shafts 21 and 22 might result in sufficient displacement of the tubes with relation to the openings in the plates 15 and 16 to cause 55 collision between the plunger or plungers 25 and the ends of the tubes, notwithstanding that the diameter of these plungers is determined merely by the desired strength of 60 material without regard to the inside diameter of the tubes, since the thrust of the plunger will be against the metallic plugs used to close the bottom of the tubes when packing same. Furthermore, the tubes may 65 have a tendency to rise as a result of vibra-

tion about the machine. To obviate the above conditions, I provide above and below the openings in each of the plates 15 and 16, rigid horizontally extending guides 41-42 spaced apart a distance substantially equaling the outside diameters of the tubes, the ends of which, if desired, may be slightly bevelled, although the rounded surface of the tubes will ensure their passage from the chains to between the guides. These guides 70 in conjunction with the succeeding fingers 19 upon each chain will ensure the accurate positioning of each tube as it approaches the position where the plungers will be operative thereon.

The plungers 25 are removably mounted in the cross head 24, so that either or both of them may be used, as desired.

Connecting the plates or frames 15 and 16 are stay rods 43.

The tubes to be fed are indicated at 44 and the cork rods therein at 45.

The operation of the herein described mechanism is substantially as follows:—

The tubes 44, before they are filled and packed with the cork composition, have inserted in one end thereof a metallic closure plug, the other end not being so closed. As the rods emerge from the baker or vulcanizer, the operator removes them from 90 their supports and places them in the hopper or chute of the ejecting mechanism with the metallic plugs upon the side thereof adjacent the plunger mechanism. These tubes will descend the runway 12, the laterally pitched wall 10 of the hopper or chute bringing any misplaced tubes into the proper position as they approach the guide walls 13 and 14.

The chains 17 and 18 cross the plane of 105 the runway 12 so that the descent of the tubes will be arrested by engagement with said chains, and the tubes will successively fall into the pocket formed by succeeding fingers 19 carried by said chains, and be advanced one at a time or in groups of two or more, corresponding with the number of plungers 25 used in the machine.

The feed mechanism with its spaced pockets will with each cycle of operation, be advanced, the feeding movement being an intermittent movement through the medium of the cam and pawl and ratchet mechanism 31, 35, 37 and 39, or 32, 36, 38 and 40, thus feeding the tube with relation to the plates 120 or frames 15 and 16 either singly or in groups, affording a dwell when the tubes are properly positioned with relation to the plates or frames 15-16, approximating the length of time required for the plunger or 125 plungers 25 to advance to their full extent in ejecting the rods, and to recede from the empty tube, so as to permit the succeeding movement of the feeding mechanism.

When the plunger or plungers 25 are re- 130

tracted to the full extent, the ends thereof will be spaced away from the horizontal guides 41 and 42 carried adjacent the plate 15, a sufficient distance to permit the pitman 27 to pass the horizontal center of the gear 26, the quantity of this movement, as the pitman is approaching and passing said center, affording an ample interval for the feeding movements of the chains 17 and 18, which when two tubes are fed will be approximately three inches only.

After each actuation of the feeding mechanism, the chains 17 and 18 will come to rest with the ends of the tube or tubes from which the cork rod is to be ejected, between the horizontal guides 41 and 42 with the axis of said tubes in alinement with the openings in the plates or frames 15 and 16 respectively.

Substantially simultaneously with the stoppage of the feeding mechanism, the plunger or plungers 25 will engage the plug at the end of the tubes and with a slow initial movement will force the rods from the tubes, effectively breaking the bond between the rod and the wall of the tube, if there be any such, before the rod will be subjected to any material pressure such as would occur if the initial speed of the plungers were greater.

As the rods are ejected from the tubes, the operator seizes them, removes the end plug therefrom, and stacks the rods or delivers them to some other mechanism.

The empty tubes, upon the next feeding movement, are removed from the machine and returned to the packer, or stored.

As the filled tubes come to position between the guides 41 and 42, and the plates or frames 15 and 16, the end of each tube will engage the plate or frame 16 with its edge projecting slightly within the edge of the opening in said plate, thus affording ample clearance in said opening, for the passage of the cork rod.

While the feeding movement of the tubes with each actuation of the feeding mechanism, when two plungers are used, will be approximately three inches, the thrust of the plungers 25 is approximately two feet. Hence the machine must have an intermittent drive as to the feeding mechanism which will effect the advance of the tubes during that slight interval when the pitman is approaching, at, and leaving the horizontal center of the crank wheel 26 while the plungers are completely retracted.

While it is preferable to remove the filled tubes directly from the baker or vulcanizer, this is not essential and the tubes may be stored after removal from the baker or vulcanizer. Since when using but a single plunger, the ejecting machine is running at but fifty per cent of its capacity, when condi-

tions are such as to require the full capacity of the machine, two plungers are used. When, however, the baker or vulcanizer is not running to capacity, but one plunger is used.

70

By gearing the actuating means for the feeding mechanism to the actuating means for the plunger or plungers, said mechanism and said plungers may be synchronized in their functions with sufficient accuracy for the purposes of the machine, thus simplifying the design of the machine and avoiding likelihood of a collision of parts through accumulated error which might occur if the feeding mechanism and the plungers were actuated from individual sources of power.

It is not my intention to limit the invention to the details of construction shown in the accompanying drawings. The essential characteristics of the machine are a storage device adapted to receive tubes in bulk, an intermittently operative feeding mechanism adapted to automatically remove the filled tubes from said storage device one at a time or in groups, and a plunger mechanism, the plungers of which move transversely of the path of movement of said feeding mechanism and operate alternately with said feeding mechanism, or when said feeding mechanism is inoperative, and I intend to claim such broadly.

Having described the invention, what I claim as new and desire to have protected by Letters Patent, is:

1. A cork rod ejector machine embodying therein a reciprocatory plunger, oppositely disposed means having openings therethrough adapted to guide said plunger, and permit the passage of a cork rod from a tube, respectively, while holding the tube against movement with the plunger, intermittently operative feeding means adapted to accurately position the tube with relation to said oppositely disposed means, and means adapted to receive tubes and position them with relation to said feeding means whereby they will be successively delivered thereto.

2. A cork rod ejector machine embodying therein a plate having an opening therethrough, the dimensions of which are such as to permit the passage of a cork rod and to engage the end of the tube about said rod, a reciprocatory plunger, guiding means therefor for holding said plunger in alinement with said opening, means adapted to receive packed tubes in bulk, an intermittently operative feeding mechanism adapted to progressively remove tubes from said means and position them with relation to said plate, and actuating means for said feeding mechanism operative while said plunger is retracted from a tube.

3. A cork rod ejector machine embodying therein a plate having an opening therethrough, the dimensions of which are such as

- to permit the passage of a cork rod and to engage the end of the tube about said rod, a reciprocatory plunger, guiding means therefor for holding said plunger in alignment with said opening, means adapted to receive packed tubes in bulk, feeding means having an endless sequence of pockets adapted to receive tubes from said last named means and convey them to adjacent 5 said plate and position them in axial alignment with said plunger, and intermittently operative actuating means for said feeding means whereby feeding movement will be imparted to the tubes while said plunger is retracted from a tube.
4. A cork rod ejector machine embodying therein a plate having an opening there-through, the dimensions of which are such as to permit the passage of a cork rod and to engage the end of the tube about said rod, a reciprocatory plunger, guiding means therefor for holding said plunger in alignment with said opening, an inclined runway upon which tubes may be deposited in bulk 10 and along which they may descend by gravity, feeding means having an endless sequence of pockets adapted to be moved across the plane of said runway, whereby tubes will pass successively from said runway into the pockets of said feeding means, and be conveyed thereby to adjacent said plate and in axial alignment with said plunger, and intermittently operative actuating means for said feeding means whereby feeding movement will be imparted to the tubes while said plunger is retracted from a tube.
5. A cork rod ejector machine embodying therein a plate having an opening there-through, the dimensions of which are such as to permit the passage of a cork rod and to engage the end of the tube about said rod, a reciprocatory plunger, guiding means therefor for holding said plunger in alignment with said opening, means adapted to receive packed tubes in bulk, oppositely disposed, parallel chains extending from adjacent said means to adjacent said plunger, each of said chains having a sequence of outwardly extending, pocket forming fingers thereon adapted to successively engage and remove tubes from said means and position them in axial alignment with said plunger, and intermittently operative actuating means for said chains whereby the tubes will be conveyed from said means towards said plate with a step by step movement and while said plunger is retracted from a tube.
6. A cork rod ejector machine embodying therein a plate having an opening there-through, the dimensions of which are such as to permit the passage of a cork rod and to engage the end of the tube about said rod, a reciprocatory plunger, guiding means therefor for holding said plunger in alignment with said opening, an inclined runway upon which tubes may be deposited in bulk and along which they may descend by gravity, oppositely disposed, parallel chains crossing the plane of said runway and extending across said plate, each of said chains having a sequence of outwardly extending pocket forming fingers thereon adapted to successively engage and remove tubes from said runway and position them in axial alignment with said plunger, and intermittently operative actuating means for said chains whereby the tubes will be conveyed from said runway towards said plate with a step by step movement and while said plunger is retracted from a tube.
7. A cork rod ejector machine embodying therein a plate having an opening there-through, the dimensions of which are such as to permit the passage of a cork rod and to engage the end of the tube about said rod, a reciprocatory plunger, guiding means therefor for holding said plunger in alignment with said opening, means adapted to receive packed tubes in bulk, oppositely disposed, parallel sprocket chains extending from adjacent said means to adjacent said plunger, each of said chains having a sequence of outwardly extending, pocket forming fingers thereon adapted to successively engage and remove tubes from said means and position them in axial alignment with said plunger, shafts carrying sprocket wheels co-operating with said chains respectively, a ratchet wheel carried by one of said shafts, a swing frame adjacent said ratchet wheel, a pawl carried by said frame and co-operating with said wheel, a shaft counter to said last named shaft, a cam carried thereby and acting upon said swing frame, and means synchronized with the actuating means for said plunger operative upon said cam shaft, said cam being so set as to actuate said swing frame when said plunger is retracted from a tube.
8. A cork rod ejector machine embodying therein a reciprocatory plunger, oppositely disposed means having openings there-through adapted to guide said plunger, and permit the passage of a cork rod from a tube, respectively, while holding the tube against movement with the plunger, guides above and below the openings in each of said means, said guides being spaced apart a distance approximating the outside dimension of the tubes, intermittently operative feeding means adapted to accurately position the tube with relation to said oppositely disposed means, and means adapted to receive tubes and position them with relation to said feeding means whereby they will be successively delivered thereto.
9. A cork rod ejector machine embodying therein a reciprocatory plunger, oppositely disposed means having openings there-through adapted to guide said plunger, and

- permit the passage of a cork rod from a tube, respectively, while holding the tube against movement with the plunger, guides above and below the openings in each of said means, said guides being spaced apart a distance approximating the outside dimension of the tubes, intermittently operative feeding means adapted to accurately position the tube with relation to said oppositely disposed means, a runway adapted to have packed tubes deposited thereon in bulk, side walls upon opposite sides of said runway, and parallel guide walls extending from said side walls to adjacent said first named oppositely disposed means, one of said side walls being laterally pitched, whereby necessity for the accuracy in the positioning of the tubes upon said runway is prevented and said tubes will be brought, with the actuation of said feeding means, with the opposite ends of succeeding tubes in alinement.
10. A cork rod ejector machine embodying therein a plate having an opening therethrough, the dimensions of which are such as to permit the passage of a cork rod and to engage the end of the tube about said rod, a reciprocatory plunger, guiding means therefor for holding said plunger in alinement with said opening, an inclined runway upon which tubes may be deposited in bulk and along which they may descend by gravity, side walls adjacent said runway, one of said walls being laterally pitched, oppositely disposed, parallel chains crossing the plane of said runway and extending across said plate, each of said chains having a sequence of outwardly extending, pocket forming fingers thereon adapted to successively engage and remove tubes from said runway and position them in axial alinement with said plunger, parallel guide walls extending from said side walls upon opposite sides of said chains, and intermittently operative actuating means for said chains whereby the tubes will be conveyed from said runway towards said plate with a step by step movement and while said plunger is retracted from a tube.
11. A cork rod ejector machine embodying therein a plate having an opening therethrough, the dimensions of which are such as to permit the passage of a cork rod and to engage the end of the tube about said rod, a reciprocatory cross head, guides therefor, a plunger carried by said cross head, a plate having an opening therein through which said plunger passes and co-operating with said cross head, guides for holding said plunger in alinement with said first named opening, a continuously rotating crank wheel, a pitman connection between same and said cross head, means adapted to receive packed tubes in bulk, oppositely disposed, parallel sprocket chains extending from adjacent said means to adjacent said plunger, each of said chains having a sequence of outwardly extending, pocket forming fingers thereon adapted to successively engage and remove tubes from said means and position them in axial alinement with said plunger, shafts carrying sprocket wheels co-operating with said chains respectively, a plurality of ratchet wheels geared to one of said shafts,

a swing frame adjacent each of said ratchet wheels, a pawl carried by each of said frames and co-operating with its associated wheel, a shaft counter to said last named shaft, a 5 plurality of cams each having rises of different heights carried by said last named shaft and acting upon said swing frames respectively, whereby said pawls may be selectively engaged with said ratchet wheels to cause said chains to be advanced to a variable extent with each actuation of said cam shaft and in proportion to the number of plungers carried by said cross head, and means synchronized with the actuating 10 means for said cross head operative upon said cam shaft, each of said cams being so set as to actuate the swing frame associated therewith only when said cross head is positioned so as to retract the plunger or plungers carried thereby from the tube or tubes. 15

14. A cork rod ejector machine embodying therein a plate having an opening therethrough, the dimensions of which are such as

to permit the passage of a cork rod and to engage the end of the tube about said rod, a reciprocating plunger, said plunger being of relatively smaller diameter than the inside diameter of a tube from which the cork rod is to be ejected, guiding means therefor for holding said plunger in alignment with said opening, means adapted to receive packed tubes in bulk, an intermittently operative feeding mechanism adapted to progressively remove tubes from said means and position them with relation to said plate, 30 and actuating means for said feeding mechanism operative while said plunger is retracted from a tube.

In witness whereof I have hereunto affixed my signature, in the presence of two subscribing witnesses, this 3d day of May, 1921. 40

CHARLES E. McMANUS.
